UNITED STATES PATENT OFFICE.

ARTHUR MÜLLER, OF CHARLOTTENBURG, NEAR BERLIN, GERMANY.

STRIKING-PLATE TILE-MAKING MACHINE.

1,366,583.

Specification of Letters Patent. Patented Jan. 25, 1921.

Application filed April 1, 1920. Serial No. 370,602.

To all whom it may concern:

Be it known that I, ARTHUR MÜLLER, a citizen of Germany, residing at Charlottenburg, near Berlin, Germany, have invented 5 certain new and useful Improvements in Striking-Plate Tile-Making Machines, of which the following is a specification.

This invention relates in general to a machine for making roofing tiles of granular 10 material such as cement and more particularly to a machine of this kind that is provided with a patting or striking plate, and in which the forming or molding of the roofing tile is carried out by striking the material 15 with a striking plate and subsequently smoothening its surface by shaving or skimming off its protuberant parts with the aid of the said plate. When this has been done the striking plate, which was pushed back- 20 ward in carrying out the shaving operation, has to be moved to the front again into the position in which it can be used for patting the next tile. When the plate is thus moved to its front position it has to be kept raised 25 so as to prevent its shaving away the materials that are heaped up in the mold and ready to be formed into a tile by patting with the striking plate.

The striking motion is brought about in 30 machines of this kind by lifting the plate vertically to its plane and quickly letting it drop again by means of cam blocks or eccentrically journaled rolls.

The shaving motion is executed by pushing 35 the striking plate backward while holding it in a slightly inclined position, the plate being guided during its backward motion by a sliding guide member. The plate is then lifted and moved forward again in 40 the same sliding guide member into the position in which it is used for striking the next brick or tile.

An advantage gained by using eccentrically journaled rolls to obtain the striking 45 motion is that the rolls enable the plate to be easily shifted to and fro. But a serious disadvantage of this arrangement is that the rolls and their pivots are subjected to very heavy stresses by the violent blows of the 50 plate.

For this reason cam blocks with straight bearing surfaces have been used instead of eccentrically journaled rolls. By rocking the cam block to and fro the striking plate 55 was swung and raised alternately about the

front and rear edges of the cam blocks. When shifted in a raised position the plate rested on one of the edges, say the left edge, of the bearing surfaces of the blocks. This gave rise to two drawbacks. One was the 60 excessive wear of this edge and attempts were made to overcome it by providing the bottom surface of the cam block with a renewable steel strip. The second drawback 65 was that the bearing of the striking plate upon the sharp edge of the cam block caused the friction and the resistance offered by the plate when moved to be considerably increased. To overcome this resistance the expedient was adopted of shifting the striking plate by a special shifting handle with the aid of interposed levers. 70

Another drawback of the known machine was that the rolls or cam blocks upon which the shifting motion was executed were displaced between guide bars. Since the space between the guide bars and the supporting beams was very prone to become filled with the material of which the tile was made when it was put into the molding box, and thus impeded the movement of the striking plate, special auxiliary devices were devised 80 to remove this disadvantage. Metal caps were provided which covered the guide bars while the molding box was being filled, 85 which were automatically moved aside when the sliding body was moved forward, and which automatically dropped into their shielding position as soon as the striking plate had been pushed into its rearmost position. 90

By the present invention the drawbacks of the known types of devices are removed.

The invention consists in providing cam blocks which are provided at either side 95 with marginal, overlapping, downwardly projecting portions or ribs that engage the two lateral surfaces or sides of the supporting beams and thus act as guide members for guiding the striking plate, when it is 100 shifted. The cam surfaces of the cam blocks consist of a horizontal flat sliding surface and two surfaces at the two ends of the block which form obtuse angles with the horizontal surface. The striking plate is lifted by 105 turning the cam block onto one of its end surfaces which also form flat sliding surfaces upon which the block stands firm so as to be secure against undesirable tilting. The cam blocks are made of one piece, as a 110

piece of cast steel, and as the striking plate is supported during shifting and at all other times upon flat surfaces of the blocks, these latter do not need to be furnished with exchangeable supporting surfaces, and offer only a small resistance when shifted. In accordance with the invention the resistance offered by a block when it is shifted is still further reduced by supporting rollers that can be swung around into operative positions being provided between the cam blocks, these rollers being arranged nearer to the rear cam blocks than to the front blocks. When these supporting rollers are swung into their operative positions, the weight of the striking plate rests partly upon the front cam blocks but mostly upon the supporting rollers. Hence the shifting backward of the plate for the purpose of shaving off the protuberant parts of the partly finished tile, and also the shifting forward of the plate in its raised position, requires but little exertion on the part of the workman. During the patting or striking operation the supporting rollers are swung into an inoperative position.

A constructional form of the invention is shown in the drawing in which—

Figure 1 is a longitudinal section of the striking plate machine on the line 1—1 of Fig. 2,

Fig. 2 is an end view of Fig. 1 viewed from the left,

Fig. 3 is a diagrammatic representation of the striking plate and its mechanism in which the plate is shown in its lowest position,

Fig. 4 is a similar representation showing the plate in the inclined position in which it is pushed backward for the purpose of brushing or shaving off protuberant portions of a partly finished tile,

Fig. 5 is another diagrammatic representation illustrating the plate in the raised position that it occupies while returning to the front or patting position.

Fig. 6 is a side view of a cam block and a supporting bar on an enlarged scale and Fig. 7 is an end view of Fig. 6.

The striking plate *a* has bearings *b* for the shaft *c* of the front cam blocks and bearings *d* for the shaft *e* of the rear cam blocks. The cam blocks *f* have four-cornered holes that fit onto the four-cornered ends of the shafts *c* and *e*. Each block *f* has a bottom flat supporting surface *g* and two flat end surfaces *h* extending so as to form obtuse angles with the bottom flat surface. The perpendiculars drawn from the center of the square hole to the supporting surfaces *g* and *h* meet these surfaces themselves, *i. e.*, they do not intersect imaginary extensions of these surfaces. Hence the surfaces that bear the weight of the striking plate hold it securely in whatever

position it is shifted into and prevent all unintended tilting of the same, no matter whether it rests on the surfaces *g* or the surfaces *h* of the cam blocks. Fixed on the shaft *c* of the front cam block is a lever *i* with a handle *i'* and on the shaft of the rear cam block a lever *k* is fixed. Both levers *i* and *k* are linked together by a rod *l*. The striking plate, the two levers *i* and *k*, and the link rod *l* form a parallelogram. Hence when the lever *i* is rocked the lever *k* is also rocked in the same measure, and the front cam blocks fixed on the shaft *c* and the rear cam blocks fixed to the shaft *e* are always turned through equal angles. The cam blocks have lateral downwardly projecting laps *z* that extend beyond the surfaces *g* and *h* and form grooves into which the supporting bars *q* fit. Above the striking plate *a*, and at the rear of its transverse middle line, a shaft *n* is journaled in bearings *m* and upon this shaft a U-shaped bow *o* is fixed. Journaled in the bent ends of the lateral limbs of this bow are wheels *p* which, when the bow *o* is in the position shown in Fig. 1, are out of engagement with the supporting bars or rails *q*, but which travel on these rails when the bow *o* is swung toward the handle *i'* into horizontal position.

Fig. 3 is a diagrammatic representation of the parts of the machine on a reduced scale in the positions they occupy in Fig. 1. The striking plate is assumed to be located above a molding box that is not shown in the drawing. By rocking the handle *i'* to and fro the striking plate is alternately lifted and permitted to suddenly drop so as to pack the material in the mold.

When the patting operation is finished the protuberant portions of the material of which the partly finished tile is formed, are shaved off, and to do this the bow *o* is turned down into the position shown in Fig. 4. This causes the rear end of the striking plate to be lifted, while the front end remains in its lowest position, and is supported by the cam blocks *f* fixed on the shaft *c*. Hence the striking plate assumes the slanting position shown in Fig. 4. On the plate now being shifted to the rear, *i. e.*, in the direction indicated by the arrow, the front bottom edge of the plate brushes over the mold and shaves off protuberant portions of the partly finished tile. The shifting of the plate is facilitated through the principal part of its weight being borne by the wheels *p*. When the striking plate has been moved to its rearmost position, the completely molded roofing tile is removed in a known manner from the mold and the mold is re-filled. Before the plate is returned to its front position the cam blocks are turned by rocking the handle *i'* into the position shown in Fig. 5. The striking plate then rests

partly upon the left inclined surfaces *h* of the front cam blocks and chiefly upon the wheels *p*.

The plate *a* is now raised and can be re-
5 stored to its patting position above the mold. This restoring movement can also be easily carried out because the greater part of the weight of the plate then also rests upon the wheels *p*.

10 I claim:

1. In a tile making machine, rails, a striking plate, bearings attached to the striking plate, cam blocks mounted and adapted to be shifted on the said rails, shafts fixed in 15 the said cam blocks and journaled in the said bearings, a handle fixed to one of said shafts, and overlapping lateral edges on the cam blocks extending along the sides of the said rails so as to form guide members for 20 guiding the blocks when shifted.

2. In a tile making machine, rails, a striking plate, bearings attached to the striking plate, cam blocks mounted and adapted to be shifted on the said rails, shafts fixed in the 25 said cam blocks and journaled in the said bearings, a handle fixed to one of said shafts, and overlapping lateral edges on the cam blocks extending along the sides of the said rails so as to form guide members for guiding 30 the blocks when shifted, said cam blocks being formed with a normally horizontal flat surface and two adjoining flat surfaces forming obtuse angles with the horizontal flat surface.

3. In a tile making machine, rails, a striking plate, bearings attached to the striking plate, front and rear cam blocks adapted to be shifted on the said rails, rollers adapted to travel on the said rails, shafts journaled 40 in some of the said bearings and fixed in the said cam blocks, a roller shaft journaled in others of the said bearings, and arms pivoted at their one end to the roller shaft and to the said rollers at their other end, the distance 45 between the pivots at both ends of one of said arms plus the radius of a roller being larger than the vertical distance between the roller shaft and the top of one of said rails.

50 4. In a tile making machine, rails, a striking plate, front and rear cam blocks adapted to be shifted on the said rails, rollers adapted to travel on the said rails, front and rear bearings attached to the striking plate and 55 associated with the front and rear rollers, front and rear shafts journaled in the front and rear blocks and fixed in the front and rear cam blocks, a roller bearing attached to the striking plate and situated nearer to the rear than to the said front bearings, a roller shaft journaled in the roller bearing, and arms pivoted at their one end to the roller shaft and at their other end to the 60 rear than to the said front bearings, a roller shaft journaled in the roller bearing, and arms pivoted at their one end to the roller shaft and at their other end to the

said rollers, the distance between the pivots at both ends of one of said arms plus the 65 radius of one of said rollers being larger than the vertical distance between the roller shaft and the top of one of said rails.

5. In a tile making machine, rails, a striking plate, front and rear cam blocks adapted 70 to be shifted on the said rails, rollers adapted to travel on the said rails, front and rear bearings attached to the striking plate and associated with the front and rear rollers, front and rear shafts journaled in the front 75 and rear blocks and fixed in the front and rear cam blocks, a roller bearing attached to the striking plate and situated nearer to the rear than to the said front bearings, a roller shaft journaled in the roller bearing, 80 and arms pivoted at their one end to the roller shaft and at their other end to the said rollers, the distance between the pivots at both ends of one of said arms plus the 85 radius of one of said rollers being larger than the vertical distance between the roller shaft and the top of one of said rails, said cam blocks being formed with a normally horizontal flat surface and two adjoining flat surfaces forming obtuse angles with the 90 horizontal flat surface.

6. In a tile making machine, rails, a striking plate, front and rear cam blocks adapted to be shifted on the said rails, rollers adapted 95 to travel on the said rails, front and rear bearings attached to the striking plate and associated with the front and rear rollers, front and rear shafts journaled in the front and rear blocks and fixed in the front and rear cam blocks, a roller bearing attached to 100 the striking plate and situated nearer to the rear than to the said front bearings, a roller shaft journaled in the roller bearing, arms pivoted at their one end to the roller shaft and at their other end to the said rollers, the distance between the pivots at both ends of one of said arms plus the radius of one 105 of said rollers being larger than the vertical distance between the roller shaft and the top of one of said rails, a handle fixed to the said front shaft, and overlapping lateral edges on the cam blocks extending along the sides of the said rails so as to form guide members for 110 guiding the cam blocks when shifted, said cam blocks each being formed with a horizontal flat surface normally resting upon one of said rails and two adjoining flat surfaces forming obtuse angles with the horizontal flat surface.

In testimony whereof I have signed this 120 specification in the presence of two witnesses.

ARTHUR MÜLLER.
